Primary Examiner—James Gandy*Assistant Examiner*—Robert M. Spear*Attorney, Agent, or Firm*—Finnegan, Henderson, Farabow, Garrett & Dunner**[57]****CLAIM**

The ornamental design for pattern for an embossed paper product, as shown and described.

DESCRIPTION

The sole FIGURE is a top plan view of a pattern for an embossed paper product embodying our design.

The broken line shown in the figure depicts the boundaries of the embossed paper product and forms no part of the claimed design.
